UNITED STATES PATENT OFFICE.

GEORGE K. CARLSON, OF NEW YORK, N. Y.

VALVE-GRINDER.

1,134,511.

Specification of Letters Patent.

Patented Apr. 6, 1915.

Application filed December 12, 1914. Serial No. 876,868.

To all whom it may concern:

Be it known that I, GEORGE K. CARLSON, a subject of the Emperor of Russia, residing at New York, in the county of New York and State of New York, have invented 5 certain new and useful Improvements in Valve-Grinders, of which the following is a specification, reference being had therein to the accompanying drawing.

10 This invention relates to valve grinders designed more particularly for grinding the valves of internal combustion engines such as are universally employed in motor vehicles, the object of the invention being to 15 produce a portable device, simple in construction, compact in form and effective in operation, and which may be manufactured at little expense.

With these ends in view my invention 20 consists in the combination with a frame or stock, of a spiral member mounted for oscillation therein and adapted to be operatively engaged with the valve to be ground, a reciprocating device guided by the frame or 25 stock and engaging the spiral member to oscillate it, and an operating member sustained by the frame or stock and connected with the reciprocating device for imparting a reciprocating movement thereto. In the 30 more specific embodiment of the invention, the frame or stock is of tubular form and provided at one end with a pressure handle, and the spiral member is in the form of a spirally formed shaft which extends longitudinally within the stock and is journaled 35 at its opposite ends in suitable bearings in the stock, the reciprocating device being in the form of a slide with opposing shoes which enter the spirals of the shaft at opposite 40 site sides, and which slide is connected by means of links, to a vibratory operating handle pivoted to the stock. The spiral shaft has connected with it, a stem formed at its extremity to be interlocked or otherwise 45 operatively engaged with the valve to be ground; whereby by the vibratory movement of the operating lever, the stem will be caused to oscillate, and will impart a corresponding movement to the valve, the required 50 site pressure being applied to hold the valve in proper frictional contact with its seat, by means of the pressure handle on the upper end of the stock.

In the accompanying drawings, I have 55 shown my invention in one form of embodiment by way of example, and includ-

ing the detailed features above enumerated, but it will be understood that the detailed construction may be variously modified without departing from the limits of the invention; and further it will be understood that the invention is not limited to any particular form or construction of the parts except in so far as such limitations are specified in the claims.

60 In the accompanying drawings: Figure 1 is a side elevation of my improved device. Fig. 2 is a longitudinal sectional elevation through the same on the line *a—a* of Fig. 1. Fig. 3 is a horizontal sectional plan view on the line *b—b* of Figs. 1 and 2.

65 Referring to the drawings, my improved device comprises as its main features a frame or stock 1, a spiral shaft 2 mounted for oscillation therein, a reciprocating device 3 provided with opposing shoes 3^a engaging the spiral of the shaft at opposite sides, and an operating member 4 sustained by the stock and connected with the reciprocating device in such manner that by the vibratory movements of the operating member, the reciprocating device will be moved longitudinally back and forth, and engaging the spiral member, will cause the same to oscillate within the frame.

70 The stock or frame is preferably of tubular form and consists of a main section 5 and an extensible section 6 which is telescoped in the upper end of the main section and is clamped adjustably therein by means of a bolt 7 extending through the main section and through longitudinal slots 8 in the extensible section, whereby the length-over-all, of the frame may be varied to meet the conditions encountered in practice. The extensible section has fixed to it a pressure handle in the form of a head 9 fixed to the end of said section, the purpose of which will presently appear.

75 The spiral member is in the form of a spirally grooved shaft which extends longitudinally within the lower end of the main section 5 of the stock, being mounted at its upper end in a central bearing in a block 10 fixed within the stock, and being mounted at its opposite end in a bearing in a block 11 fixed in the lower end of the stock. The reciprocating device 3 before alluded to as being in the form of a slide with opposing 80 shoes, is substantially circular in form to fit and slide within the tubular stock, and is provided with an open slot which embraces

the spiral shaft and the sides of which slot are shaped to form the opposing shoes 3^a which engage the spiral of the shaft at opposite sides. The slide is guided in the tubular stock by means of lugs 3^b projecting outwardly from its opposite sides and extending through longitudinal slots 5^a in the opposite sides of the stock. The operating member 4 is in the form of a lever provided at its 5 inner end with forked parallel arms 13 which extend at opposite sides of the stock above the bearing block 10, at which point the arms are pivoted to the stock on a transverse axis as at 13^a so that the lever may be 10 vibrated up and down. The arms 13 are connected with the slide by means of two links 14, the lower ends of which are pivoted to the lugs 3^b while their upper ends are pivoted to the said arms. As a result of this 15 construction and arrangement of the parts, when the operating lever is vibrated up and down, the slide will be reciprocated back and forth, and engaging the spiral shaft it will cause the same to oscillate back and forth. 20 The lower end of the spiral shaft is extended outwardly through the bearing block 11 and has connected with it a stem 15, the lower end of which is formed so as to be operatively connected with the valve to be ground, 25 the end of the stem in the present instance being flattened so as to enter the slot which is usually formed in the valves of internal combustion engines.

In the use of the device, the spring, which 30 is usually applied to the valves of internal combustion engines and which normally tends to hold the valve yieldingly on its seat is removed, and a light spring is substituted which is seated around the valve stem and 35 bears against the under side of the valve so that it will tend to lift the same off its seat, the use of this substitute spring being temporary and merely to facilitate the grinding operation. The valve grinder is now 40 engaged with the valve by inserting the widened end of its stem 15 in the slot in the valve, or by otherwise effecting operative connection between the stem 15 and the valve. A suitable abrasive material is next 45 applied between the valve and valve seat, and with the grinding device held in the position described, and the proper pressure being applied to the same by means of the pressure handle 9 so as to hold the valve 50 against its seat, the operating lever 4 is vibrated up and down, with the result that the spiral shaft will be oscillated back and forth, thereby imparting a corresponding motion 55

to the stem 15, which in turn will impart a like motion to the valve, thereby causing the 60 same to oscillate back and forth in contact with its seat. This operation is continued until all the irregularities in the co-operating surfaces have been removed and the contacting parts of the valve and seat are perfectly smooth and regular. 65

The device as a whole, possessing the above described features of construction and characteristics, is portable in character, simple in construction and compact in form, 70 and may be conveniently applied to the valves and operated to speedily grind the parts and bring them to proper operative condition.

Having thus described my invention, what 75 I claim is:

1. In a valve grinder, the combination of a frame, a spiral member mounted for oscillation therein and adapted to be operatively engaged with the valve to be ground, a reciprocating device engaging said spiral member, a hand lever pivoted at its inner end to the frame to swing up and down, and a link jointed at one end to the lever at a point between the ends of the latter, and 80 jointed at its other end to said reciprocating device.

2. In a valve grinder, the combination of a stock, a spiral member mounted for oscillation therein and adapted to be operatively engaged with the valve to be ground, a reciprocating device engaging said spiral member, an operating lever provided at its inner end with forked parallel arms extending on opposite sides of the stock and pivoted thereto on a transverse axis, and links 90 connecting said arms respectively with the opposite sides of the reciprocating device. 95

3. In a valve grinder, the combination of a tubular stock provided with longitudinal 100 slots, upper and lower bearing blocks fixed therein, a spiral member journaled in bearings in said blocks for oscillation and adapted to be operatively engaged with the valve to be ground, a reciprocating device in the 105 form of a slide engaging said spiral member and provided with lugs extending through said slots, and an operating member sustained by the stock and connected with said lugs. 110

In testimony whereof, I have affixed my signature in presence of two witnesses.

GEORGE K. CARLSON.
